Troy Higdon, Logan Higdon Atty:

UNITED STATES PATENT OFFICE.

WILLIAM SANDERS, OF ST. LOUIS, MISSOURI.

DESIGN FOR A CHURN-FRAME.

SPECIFICATION forming part of Design No. 27,188, dated June 8, 1897.

Application filed February 1, 1897. Serial No. 621,565. Term of patent 7 years.

To all whom it may concern:

Be it known that I, WILLIAM SANDERS, of the city of St. Louis, State of Missouri, have invented a new and original Design for Churn-Frames, of which the following is a full, clear, and exact description, reference being had to the accompanying drawings, forming a part hereof.

Figure 1 is a top plan view of a churn-frame embodying my new design. Fig. 2 is a side elevation of the parts shown in Fig. 1 and looking in the direction indicated by the arrow.

As shown in the drawings, the leading and essential feature of my design consists of the horizontal bar 3; the bracket 4, projecting upwardly from the rear end of said horizontal bar; the arm 5, projecting upwardly from the front end of said horizontal bar; the arm 6, projecting upwardly from said horizontal bar at a point half-way between the bracket 4 and the center of the bar; the horizontal bar 7, projecting forwardly from the upper end of the arm 6; the inclined bar 8, connecting the forward end of the bar 7 with the upper end of the arm 5; the cylindrical body 9, projecting laterally from the junction of the upper end of the arm 5 with the inclined bar 8; the bar 10, resting upon the bar 7 and projecting backwardly to a point in alinement with the rear end of the bracket 4; the bar 11, projecting laterally from the front end of the bar 10; the bar 12, connecting the forward end of the bar 10 with the end of the bar 11 opposite the bar 10, and the bracket 13, projecting upwardly from the bar 12 to a point in alinement with the junction of the bar 12 with the bar 11.

The horizontal bar 3 is T-shaped in cross-section between the lower ends of the arms 5 and 6, and said horizontal bar 3 is flat in front of the lower end of the arm 6. The cylindrical lug 14 projects upwardly from the upper end of the bracket 4, and a similar lug 15 projects downwardly from the rear end of

the bars 10 and 12, said lugs 14 and 15 being in vertical alinement. The arm 6 is T-shaped in cross-section, the laterally-projecting rib being upon the left side of said arm to a point near the lower end of the arm, and then there is a break in said laterally-projecting rib upon the left side of the arm, and a similar rib projects from the opposite side of the arm, as indicated in dotted lines in Fig. 2. An opening 16 is formed horizontally through the arm 6 at the center of the rib which projects from the right side of said arm.

The arm 5 and the bar 8 are T-shaped in cross-section, said arm and bar being flat upon the right side, and the bar 7 is T-shaped in cross-section, said bar 7 being flat upon the top side. A bracket 17 projects downwardly and backwardly from the junction of the forward end of the horizontal bar 3 with the arm 5. A circular lug 18 projects downwardly from the horizontal ribs of the bar 7 upon each side of the vertical rib of said bar. A cylindrical body 19 projects upwardly and downwardly from the upper end of the bracket 13, and a cylindrical lug 20 projects downwardly from the junction of the bars 11 and 12 in alinement with the cylindrical body 19. An opening 21 is formed horizontally through the cylindrical body 19, and an opening 22 is formed vertically through the lug 15, and a similar opening is formed through the circular lug 14 in alinement with said opening 22. An opening 23 is formed vertically through the cylindrical body 19, and a similar opening is formed through the lug 20 in alinement with said opening 23.

I claim—

The design for a churn-frame, substantially as herein shown and described.

In testimony whereof I affix my signature in presence of two witnesses.

WILLIAM SANDERS.

Witnesses:

EDWARD E. LONGAN,
MAUD GRIFFIN.
